WILBERT A. SPRIZE, OF WISCONSIN RAPIDS, WISCONSIN

AUTOMATIC PAPER FEED AND ALIGNER

Application filed February 4, 1929. Serial No. 337,353.

This invention relates to an automatic paper feed and aligner for duplicators and other reproducing machines, for expeditiously feeding and properly aligning paper or other sheets to be impressed from an adhesive duplicating web or film.

A further object of the invention is to provide, in a manner as hereinafter set forth, an automatic paper feed and aligner for duplicators so constructed and arranged whereby the duplicating film or web coacts therewith to align and position the sheet to be impressed in the path of the pressing roller of the machine.

15 A further object of the invention is to provide, in a manner as hereinafter set forth, an automatic paper feed and aligner for duplicators and other reproducing machines, and with the device including a carrier for a pack 20 of sheets to be successively impressed, the carrier being provided at its bottom with a throat for the successive passage of the sheets discharged from the carrier, and with the device including a tensioned follower element acting 25 on the pack of sheets to maintain the lowermost sheet of the pack against the bottom of the carrier, and further with the device so constructed and arranged to be shiftable towards and from the adhesive duplicating 30 web or film for the latter to coat with the carrier to withdraw, align and position the sheet in the path of the pressing roller of the machine whereby when such roller is moved against the sheet, the latter will be spread 35 throughout upon the film or web and taken up an impression therefrom.

Further objects of the invention are to provide, in a manner as hereinafter set forth 40 an automatic paper feed and aligning device for duplicators and other reproducing machines which is simple in its construction and arrangement, strong, durable, thoroughly efficient in its use, conveniently operated, readily installed with respect to the sheet, 45 and comparatively inexpensive to manufacture.

With the foregoing and other objects in view the invention consists of the novel construction, combination and arrangement of 50 parts as hereinafter more specifically de-

scribed, and illustrated in the accompanying drawings wherein is shown an embodiment of the invention, but it is to be understood that changes, variations and modifications can be resorted to which fall within the scope of the claims hereunto appended.

55 In the drawings wherein like reference character denote corresponding parts throughout the several views:—

Figure 1 is a top plan view of an automatic 60 paper feed and aligner device in accordance with this invention.

Figure 2 is a side elevation of the device showing the adaptation thereof with respect 65 to a duplicating machine and with the device in lowered position.

Figure 3 is a section on line 3—3 of Figure 1.

Figure 4 is a longitudinal sectional view of 70 the device with respect to a duplicating machine and with the device in elevated position.

Figure 5 is a fragmentary view in elevation of the pressing roller and its support.

Figure 6 is a sectional detail.

Referring to the drawings in detail a duplicating machine of known construction is indicated at 1 and which includes, as is well known, an adhesive duplicating film, web or apron 2, hereinafter termed a film and which winds off and on the rollers 3, 4. Adjacent 75 the outer face of one side of the frame of the machine a track member 5 is arranged and supported in spaced brackets 6. The machine further includes a platform 7 for supporting the film 2 between the rollers 3, 4. The platform 7 has depending ends of arcuate cross section over which the film 2 passes. The foregoing elements are illustrated for the purpose of clearly showing the adaptation of a device, in accordance with this invention, 80 with respect to a duplicating or reproducing machine.

90 In duplicating machines, they include a pressing roller the function of which is to press a sheet of paper upon the film 2 for the purpose of taking up an impression by the sheet from the film 2. The pressing roller when functioning is shifted from the rear to the forward end of the machine. The pressing roller is carried by a suitable support 95 100

which is slidably mounted on the track member 5. The form of support for the pressing roller as disclosed is different from the form now employed. The support as illustrated 5 is indicated at 8 and is of yoke-shaped contour. Pivotally mounted in the arms of the support is the pressing roller 9 which is of a diameter to project from the inner edge of the support 8. See Figure 4. One of the 10 arms of the support, such arm being indicated at 10 is formed with an apertured extension 11 for the purpose of slidably mounting the support on the track member 5. The extension 11 is formed with a lug or protuberance 12 which constitutes a stop when the support 8 is thrown to its outward position or rather 15 when the pressing roller 9 is moved to inactive position and which is in a direction away from the machine. When the roller 9 is in 20 active position it extends transversely with respect to the film 2. The support 8 also constitutes a hand grip when moving the pressing roller 9 from the rear end to the forward end of the machine for the purpose of providing an impression on the sheet of paper 25 which the roller 9 travels over.

The device includes a carrier in the form of a rectangular tray of the desired length, width and height and referred to generally 30 at 13. The tray consists of a bottom 14, a rear end wall 15 and a pair of side walls 16. The bottom 14 in proximity to the rear end wall 15 is provided with a transversely extending, rectangular slot 17 co-extensive with 35 the width of the bottom 14. The side walls 16 at the ends of the slot 17 are curved in an arch-like manner as indicated at 18. The slot 17 provides in connection with the curved edges of the sides of the tray at the ends of 40 the slot a concaved throat for the successive discharge of the sheets of the pack of sheets 19 which are arranged or supported by the tray 13. The manner in which the throat is formed permits a portion of the adhesive tape 45 to project slightly above the bottom of the tray and make contact with the bottom sheet of paper of the pack when the tray is in its lowermost position, therefore eliminating a depressor arrangement for the sheets. The 50 end portion 14' of the bottom forms a support for one end of a pack of sheets.

The sheets of the pack 19 correspond to the interior length and width of the tray 13. The sheets of the pack 19 are indicated at 55

Each of the side walls 16, at a point directly in advance of the slot 17 is formed with an inwardly extending lug 21 to prevent the pack from shifting over the top edges of the tray. Each side wall 16 in proximity to the forward end is formed with a vertically disposed lug 22 formed with an aperture 23. The end wall 15 has connected thereto an upstanding handle piece or member 24.

The forward end of the tray 13 is supported above and pivotally connected with

the sides of the frame of the machine 1 and for such purpose an inverted, yoke-shaped member is provided and which includes a top portion 25 and a pair of side portions 26 which depend from the ends of the portion 25. The portion 25 is of greater length than the width of the tray 13 and the frame of the machine and said portion 25 is secured to the lower face of the bottom 14 of the tray 13, is flush with the forward edge of said bottom 14 and projects laterally from each of the sides of the tray at the bottom of said sides. Secured to each side of the frame of the machine below the top edge of the side is a bearing device or member for pivotally supporting the lower ends of the portions 26 whereby the tray is pivotally connected with the machine frame. With reference to Figure 6 the construction of each bearing member is shown and it consists of a disc 27 positioned against the upper face of the side of the machine frame. Centrally of the outer face of the disc 27 is a shank 28 which is mounted in an opening 29 formed in the side 30 of the machine frame. The shank 28 projects inwardly from said side 30 and is threaded. Engaging with the threaded portion of the shank is a securing nut 31 for maintaining the bearing member in position.

The outer face of the disc 27, centrally thereof has extending therefrom a pivot 32 for the lower end of a portion 26 of the yoke-shaped member and the pivot 32, which constitutes a bearing extends through an opening 33 formed in the portion 26 of the yoke-shaped member. The portions 26 of the yoke-shaped member are the arms thereof. The discs 27 space the arms 36 from the sides 30 of the machine frame.

The tray 13 has pivotally connected to the sides thereof forwardly of the slot 17 a pair of supporting arms 34 each provided with an inwardly extending lug 35. The arms 34 are provided for maintaining the rear of the tray in an elevated position when the device is not employed for feeding and aligning purposes. The normal position of the arms 34 are as illustrated in Figure 2 and with the lugs 35 engaging the tray to arrest the upward shifting movement of the arms relative to the tray. When the arms 34 are employed to maintain the rear of the tray in an elevated position, said arms are swung to a vertical position and rest on the frame of the machine.

Pivotally connected with the tray is a tensioned follower element which normally seats on the top of the pack 19 and acts to maintain the lower sheet of the pack against the bottom of the tray. The follower element or member is constructed of a length of wire of the desired gauge and it includes a V-shaped portion 36 having a flat rear end 37. That part of the portion 36 from the flat end 37 is curved upwardly and includes a pair of right angularly disposed portions 38, 39 which extend

into the apertures 23 of the lugs 22. The portion 38 is formed with an extension 40 depending with respect to a lug 22 and having its lower end connected to a tensioning spring 41. The extension 40 is arranged exteriorly of one of the sides 16 of the tray.

The tensioning spring 41 has its lower end connected to the lower end of the extension 40 and its upper end anchored to a side 16 of the tray. The tensioning spring 41 inclines upwardly from the lower end of the portion 26 to the forward end of such spring.

When the tray 13 has the rear thereof in lowered position, it opposes the curved rear end of platform 7 and the adhesive film 2 will extend up into the throat formed by slot 17 and adhere to the lowermost sheet of the pack 19, but the point of adherence between the film 2 and sheet is in advance of the rear end 20 of the latter. The tray 13 is then elevated from its rear and such action causes the rear end of the sheet to pass through the throat formed by the slot 17 and the sheet which is indicated at 20, when the tray is raised to the desired height will be in the position shown in Figure 4 of the drawing and in advance of the pressing roller 9. It will be observed that the sheet 20 has its rear end projected beyond the roller 9 and this end enables the sheet 20, after being impressed to be quickly removed from the film 2. After the sheet 20 is in the position as shown in Figure 4, the pressing roller 9 is shifted in the direction of the arrow 42, such action completely withdrawing the sheet 20 from the tray and causing the sheet to be positioned on the film 2 so that an impression will be made from the latter on to the sheets. After the impression has been made on the sheet 20, the latter is removed from the film 2 and an operation similar to the foregoing is again carried out. The sheet is of a size whereby roller 9 will move clear thereof before the roller contacts with the support for the tray. The extended rear end 45 of the film or that portion of the sheet 20 which projects rearwardly from the roller 9 is indicated at 43. See Figure 4. The tensioning element tends to shift the pack towards the bottom 14 of the tray as the lowermost sheet 20 is being withdrawn from the tray, due to the action of the pressing roller 9.

It is thought the many advantages of an automatic paper feed and aligning device, in accordance with this invention for lubricators and reproducing machines can be readily understood, and although the preferred embodiment of the invention is as illustrated and described, yet it is to be understood that changes in the details of construction can be had which fall within the scope of the invention as claimed.

What I claim is:

1. A sheet feeding and aligning device for duplicating machines comprising a sheet pack carrier for positioning over the adhe-

sive duplicating film of the machine, said carrier including a pair of side walls, a rear wall and a bottom, means for permanently supporting the forward end of the carrier in an elevated position with respect to and for pivotally connecting it with the machine, the rear end of said carrier being adapted to be shifted towards and from said film, said sides and bottom adjacent said rear wall having means to provide a concaved throat for the entrance of a portion of the film to adhere to the lowermost sheet of the pack, in advance of the rear end of such sheet when the rear end of the carrier is lowered whereby when the latter is elevated the film will withdraw the rear portion of the sheet through the throat and position such portion in the path of the pressing roller of the machine.

2. A sheet feeding and aligning device for duplicating machines comprising a sheet pack carrier for positioning over the adhesive duplicating film of the machine, said carrier including a pair of side walls, a rear wall and a bottom, means for permanently supporting the forward end of the carrier in an elevated position with respect to and for pivotally connecting it with the machine, the rear end of said carrier being adapted to be shifted towards and from said film, said sides and bottom adjacent said rear wall having means to provide a concaved throat for the entrance of a portion of the film to adhere to the lowermost sheet of the pack, in advance of the rear end of such sheet when the rear end of the carrier is lowered whereby when the latter is elevated the film will withdraw the rear portion of the sheet through the throat and position such portion in the path of the pressing roller of the machine, and a tensioned, follower element for the sheet pack, said element being pivotally connected with the sides of said carrier.

3. A sheet feeding and aligning device for duplicating machines comprising a sheet pack carrier for positioning over the adhesive duplicating film of the machine, said carrier including a pair of side walls, a rear wall and a bottom, means for permanently supporting the forward end of the carrier in an elevated position with respect to and for pivotally connecting it with the machine, the rear end of said carrier being adapted to be shifted towards and from said film, said sides and bottom adjacent said rear wall having means to provide a concaved throat for the entrance of a portion of the film to adhere to the lowermost sheet of the pack, in advance of the rear end of such sheet when the rear end of the carrier is lowered whereby when the latter is elevated the film will withdraw the rear portion of the sheet through the throat and position such portion in the path of the pressing roller of the machine, and said carrier being in the form of a tray open at its forward end and closed at its rear end.

4. A sheet feeding and aligning device for duplicating machines comprising a sheet pack carrier for positioning over the adhesive duplicating film of the machine, said carrier including a pair of side walls, a rear wall and a bottom, means for permanently supporting the forward end of the carrier in an elevated position with respect to and for pivotally connecting it with the machine, the rear end of said carrier being adapted to be shifted towards and from said film, said sides and bottom adjacent said rear wall having means to provide a concaved throat for the entrance of a portion of the film to adhere to the lowermost sheet of the pack, in advance of the rear end of such sheet when the rear end of the carrier is lowered whereby when the latter is elevated the film will withdraw the rear portion of the sheet through the throat and position such portion in the path of the pressing roller of the machine, and said carrier at its top being provided with sheet pack retaining lugs.

5. A sheet feeding and aligning device for duplicating machines comprising a sheet pack carrier for positioning over the adhesive duplicating film of the machine, said carrier including a pair of side walls, a rear wall and a bottom, means for permanently supporting the forward end of the carrier in an elevated position with respect to and for pivotally connecting it with the machine, the rear end of said carrier being adapted to be shifted towards and from said film, said sides and bottom adjacent said rear wall having means to provide a concaved throat for the entrance of a portion of the film to adhere to the lowermost sheet of the pack, in advance of the rear end of such sheet when the rear end of the carrier is lowered whereby when the latter is elevated the film will withdraw the rear portion of the sheet through the throat and position such portion in the path of the pressing roller of the machine, and a handle member extending upwardly from the rear end of the carrier.

6. A sheet feeding and aligning device for duplicating machines comprising a sheet pack carrier for positioning over the adhesive duplicating film of the machine, said carrier including a pair of side walls, a rear wall and a bottom, means for permanently supporting the forward end of the carrier in an elevated position with respect to and for pivotally connecting said end with the machine, the rear of said carrier being adapted to be shifted towards and from said film, said carrier having its bottom and side walls formed with means to provide a throat for the entrance of a portion of the film to adhere to the lower face of the lowermost sheet of the pack adjacent the rear end of the sheet when said rear end of the carrier is lowered whereby when such end is elevated the rear end portion of the sheet will be withdrawn

by the film and positioned in the path of the pressing roller of the machine.

7. A sheet feeding and aligning device for duplicating machines comprising a sheet pack carrier for positioning over the adhesive duplicating film of the machine, said carrier including a pair of side walls, a rear wall and a bottom, means for permanently supporting the forward end of the carrier in an elevated position with respect to and for pivotally connecting said end with the machine, the rear of said carrier being adapted to be shifted towards and from said film, said carrier having its bottom and side walls formed with means to provide a throat for the entrance of a portion of the film to adhere to the lower face of the lowermost sheet of the pack adjacent the rear end of the sheet when said rear end of the carrier is lowered whereby when such end is elevated the rear end portion of the sheet will be withdrawn by the film and positioned in the path of the pressing roller of the machine, and said supporting means including bearing members adapted to be secured to the frame of the machine.

8. A sheet feeding and aligning device for duplicating machines comprising a sheet pack carrier for positioning over the adhesive duplicating film of the machine, said carrier including a pair of side walls, a rear wall and a bottom, means for permanently supporting the forward end of the carrier in an elevated position with respect to and for pivotally connecting said end with the machine, the rear of said carrier being adapted to be shifted towards and from said film, said carrier having its bottom and side walls formed with means to provide a throat for the entrance of a portion of the film to adhere to the lower face of the lowermost sheet of the pack adjacent the rear end of the sheet when said rear end of the carrier is lowered whereby when such end is elevated the rear end portion of the sheet will be withdrawn by the film and positioned in the path of the pressing roller of the machine, said supporting means including bearing members adapted to be secured to the frame of the machine, and a tensioned follower element for the sheet pack, said element connected to the sides of the carrier.

9. A sheet feeding and aligning device for duplicating machines comprising a sheet pack carrier of tray like form for positioning over the adhesive duplicating film of the machine, said carrier having inherent means at its sides and bottom and adjacent the rear end of its bottom to provide a throat for the entrance into the carrier of a portion of said duplicating film, said carrier adapted to be shifted towards and from said film and when shifted towards the latter providing for the entrance of a portion of the film to adhere to the lower face of the lower sheet of the

5 pack, adjacent the rear end of such sheet whereby when the rear end of the carrier is elevated the rear end portion of the sheet will be withdrawn by the film and positioned in the path of the pressing roller of the machine.

10. A sheet feeding and aligning device for duplicating machines comprising a sheet pack carrier for positioning over and adapted to have its rear end moved towards and from the adhesive duplicating film of the machine, means for permanently supporting the forward end of the carrier in an elevated position with respect to and for pivotally connecting said forward end with the machine, said carrier having its sides and its bottom forwardly of the rear end of the latter provided with inherent means to form a throat for the entrance of a portion of the film to 20 adhere to the lower face of the lowermost sheet of the pack, forwardly of the rear end of said sheet when said rear end of the carrier is lowered whereby when the rear end of the carrier is elevated the rear portion of the 25 sheet will be withdrawn by the film and positioned in the path of the pressing roller of the machine.

11. A sheet feeding and aligning device for duplicating machines comprising a sheet 30 pack carrier for positioning over the adhesive duplicating film of the machine, said carrier being in the form of a tray like body having its bottom in advance of the rear end thereof and its sides in advance of the rear 35 end thereof formed with inherent means to provide a concave throat for the entrance of a portion of the duplicating film of the machine to adhere to the lowermost sheet of the pack of sheets in the carrier for with- 40 drawing such sheet and positioning it in the path of the pressing roller of the machine, said carrier being connected with the machine to have its rear end movable towards and from the film.

45 In testimony whereof, I affix my signature hereto.

WILBERT A. SPRICE.
